UNITED STATES PATENT OFFICE.

BEN J. FELDSTEIN, OF NEW YORK, N. Y.

BABY RATTLE.

Application filed May 29, 1925. Serial No. 33,689.

To all whom it may concern:

Be it known that I, BEN J. FELDSTEIN, a citizen of the United States of America, residing at New York city, New York, have 5 invented new and useful Improvements in Baby Rattles, of which the following is a specification.

This invention relates to toys and especially to such devices as are commonly 10 called baby or nursery rattles.

The object of the invention is to provide a rattle of this character with a head portion resembling that of a small child or animal having transparent eye chambers enclosing 15 loosely disposed shot adapted to represent pupils capable of being rolled about and to assume different positions, making the same very amusing and attractive.

The invention is illustratively exemplified 20 in the accompanying drawings, in which, Figure 1 is a front elevational view of the rattle; Figure 2 is a vertical sectional view taken on line 2—2 of Figure 1; and Figure 25 3 is a transverse sectional view of the rattle taken on the line 3—3 of Figure 1.

Referring to the drawing, 10 denotes a holder comprising a stem, lower ring 11 and cap 12 rigidly attached to the upper end of the stem. These and other parts of the rattle are preferably made of celluloid or some 30 other suitable, durable and sanitary material.

Secured to the cap 12 is a hollow sounding head 13 comprising two sections 14 and 15, the former conforming to the back of a small child's head, while the latter section 15 constitutes the face portion, the features of which are molded and stand out in relief. The portions of the face corresponding 40 to the positions of the eyes, are depressed round sockets 16, each thereof having a marginal annular groove 17 and center depression 18. Disposed over each socket 16 is a cup shaped transparent globe 19, the open edge of which is seated in and permanently fixed in the socket, while the closed 45 globular portion stands outwardly of the rest of the features of the face. Each globe 19 virtually comprises a transparent chamber in which a shot or bead 20 is loosely disposed, the shot being adapted to assume any 50 position in the groove 17 or be moved across

the socket to rest in the center depression 18. The hollow head portion 13 is adapted to contain a plurality of pebbles 21 or their 55 equivalent, for making a rattling noise when the device is shaken in the usual manner.

In order to cause the eyes to assume different positions in their respective sockets, it is merely necessary to shake the rattle 60 while holding it either in a vertical or horizontal position. The shot 20 will then travel in circular paths over the grooves 17 or across the bottom walls of the sockets and rest in the center depression 18. 65

What I claim is:—

1. The herein described rattle, comprising a holder, a hollow sounding head secured thereto, means loosely disposed in said head to cause a rattling noise when the rattle is 70 shaken, one face of the head having human features provided with eye sockets, transparent globular members for said sockets adapted to form an eye chamber, and balls loosely arranged in said chambers to give 75 the appearance of pupils.

2. The herein described rattle, comprising a holder, a hollow sounding head secured thereto, means loosely disposed in said head to cause a rattling noise, said head comprising 80 a section having human features in relief, the eye sockets having the bottom walls provided with annular grooves and center depressions, a transparent globe for each socket comprising a cup shaped member 85 having its open edge permanently attached to the head, and a shot for the interior of each globe.

3. An article of manufacture comprising 90 a casing made of sheet material, eyes formed by depressions in the surface thereof, said depressions being of circular shape, a pair 95 of hollow, transparent substantially hemispherical members affixed to the edges of said depressions to form two complete eye sockets and each socket having a small sphere therein representing an eyeball or pupil and capable of motion within the eye socket and free to make a rattling noise when agitated. 100

In testimony whereof I have affixed my signature.

BEN J. FELDSTEIN.
